UNITED STATES PATENT OFFICE.

PAUL BURKE, OF GREEN BAY, WISCONSIN, ASSIGNOR TO NORTHWEST ENGINEERING COMPANY, OF GREEN BAY, WISCONSIN, A CORPORATION OF WISCONSIN.

POWER SHOVEL.

Application filed December 30, 1922. Serial No. 609,782.

To all whom it may concern:

Be it known that I, PAUL BURKE, a citizen of the United States of America, and a resident of the city of Green Bay, Brown County, Wisconsin, have invented certain new and useful Improvements in Power Shovels, of which the following is a specification.

This invention relates to power shovels, and more particularly to that type of shovel in which the hoisting rope or cable is used to effect the thrust.

The object of the invention is to provide a rope-thrusting shovel having a single part hoist line for lifting and thrusting the dipper and cooperating with other means to effect the reciprocation of the dipper handle or stick, without the usual gear mechanism or rack and pinions or auxiliary driving apparatus of any kind.

A further object of the invention is to provide a novel construction of guiding mechanism for the dipper handle.

The invention further consists in the several features hereinafter set forth and more particularly defined by claims at the conclusion hereof.

In the drawings: Fig. 1 is a side elevation of a power shovel mechanism embodying the invention; Fig. 2 is a plan view thereof, partly in section; Fig. 3 is a vertical sectional view through the stick guiding mechanism; Fig. 4 is a detail side view of the saddle block and guide; Fig. 5 is a plan view, partly in section, of the structure shown in Fig. 4 with the saddle block removed.

In the drawings the numeral 6 designates the boom, which may be of any suitable construction, vertically pivotally attached at its lower end to the rotating base 7 of the machine, said base being of well-known construction. A hoisting drum 8 and an auxiliary drum 9 are mounted on the base 7 in any suitable manner and driven from the prime mover (not shown) on the base. The drums 8 and 9 may be of any well-known construction equipped with clutches and brakes (not shown) of any standard or approved construction to control their operation. The boom is adapted to be raised or lowered in various positions of vertical adjustment by any well-known means, such as a cable 10 connecting pulleys 11 at the outer end of the boom to parts on the rotating

base. The boom shown is of the plate-girder type with the dipper handle or stick 12 working between its sides 13.

The shipper shaft 14 is secured in brackets 15 on the boom and the saddle block 16 is loose on the shaft. The saddle block 16 has a yoke portion 17 secured to journal portions 18 by U-bolts 19. The dipper handle 12 is preferably a single member having a metal covering 20. This handle is mounted to slide between the adjacent saddle block 16 and a flanged roller and sheave 21 loosely mounted on the shaft 14. The dipper or shovel 22 carried by the stick may be of any suitable construction.

The roller 21 is provided with a cable guide groove 23 receiving the cable 24 from the drum 9, said cable passing from said drum under a sheave 25, thence over roller 21 and having its outer end 24' anchored at the lower end of the stick 12.

The dipper handle has a sheave 26 mounted on its upper end and a sheave 27 mounted at its lower end, and where the shovel is designed to swing away from the machine while digging said sheave 27 is at the front side of the stick.

The hoisting cable 28 passes from the drum 8 over a sheave 29 at the outer end of the boom 6 thence over the sheave 27 and up along the stick through a slot 30 in the saddle block, then over the sheave 26 and is then dead-ended on the boom. Thus, it will be noted that the bight of the cable formed by passing around the pulley 26 has an end thrust engagement with the stick. The dead-end connection here shown comprises an eyed member 31 mounted on a pin 32 carried by extension arms 33 of the parts 18 of the saddle whereby the cable anchorage turns with the saddle block when the dipper handle swings, sleeves 34 positioning the member 31 centrally on the pin 32. The casting 35 at the upper end of the stick and carrying the sheave 26 has a stop projection 36 that may engage the roller 21 to limit the outward movement of the stick.

With the construction above described, when the drum 9 is prevented from turning by its brake, thereby holding the line or cable 24, and the line 28 is pulled in, the dipper moves in the arc of a circle of which the dipper shaft is the center. If it is desired to crowd further into the bank or move the dipper farther out, as in loading a

wagon, the braking effect on the line 24 is released slightly whereupon the line 28 pulling on the upper end of the dipper stick, through connections previously described, 5 forces the dipper stick outward. Conversely, if it is desired to move the dipper farther in or toward the boom, releasing the brake on line 28 and pulling in on line 24 produces this effect. Thus, by the proper manipulation 10 and control of the lines 24 and 28 any desired swinging or thrusting movement of the dipper and its shaft may be effected. Furthermore, by the sheave arrangement above described the thrusting action is twice 15 as great as the lifting action on the dipper. It will also be noted that the thrusting action on the dipper is proportional to the load upon the dipper and to the resistance and weight of the material it encounters during 20 digging.

It will be further noted that the line 28 forms a single hoisting line from the hoisting drum to the dipper stick and that it is not wound around any of the sheaves over 25 which it passes so that it will experience a minimum of wear.

The construction above described possesses the advantages of the usual and far more complicated shovels and yet is so simple that it will not readily get out of order and, if it does, repairs can be made by even an unskilled mechanic.

I desire it to be understood that this invention is not to be limited to any particular 5 arrangement or construction of parts except in so far as such limitations are specified in the claims.

What I claim as my invention is:

1. In an excavating shovel, the combination 0 with the supporting boom, of a dipper and dipper handle mounted thereon to shift and swing with respect thereto, of a dipper hoisting and thrusting cable having a bight in end-thrust engagement with said dipper 5 handle for crowding the dipper and another part for hoisting, and separate means for moving said dipper inwardly.

2. In an excavating shovel, the combination 0 with the supporting boom, of a dipper and dipper handle mounted thereon to shift and swing with respect thereto, of a dipper hoisting and thrusting cable having a bight in end-thrust engagement with said dipper 5 handle for crowding the dipper and another part for hoisting, and another cable for 10 moving the dipper inwardly.

3. In an excavating shovel, the combination with the supporting boom, of a shipper shaft mounted on the boom, a flanged guide roller on said shaft for the dipper handle 60 having a medial cable-receiving groove, a saddle-block on said shaft having a cable groove in its transverse portion, a dipper handle mounted to slide between said roller and block, a hoisting drum, a cable extending from said drum over the groove in said roller and connected to the lower end portion of the dipper handle, sheaves at the upper and lower end portions of the dipper handle, a sheave on the outer end portion 70 of the boom, a second hoisting drum, a hoisting and thrusting cable passing from said drum over the sheave on the boom, thence around the lower sheave on the handle and through the groove in said saddle-block and over the upper sheave on the handle to the boom, and a swinging anchorage connection with the boom for said last-named cable.

4. In an excavating shovel, the combination 80 with the supporting boom, of a dipper and dipper handle mounted thereon to shift and swing with respect thereto, and a dipper hoisting and thrusting cable having a bight in end-thrust engagement with said 85 dipper handle for crowding the dipper into the material to be excavated and another part for hoisting.

5. In a power shovel the combination of a boom, a dipper and dipper handle mounted 90 thereon for swinging and bodily lengthwise shifting movements, a dipper hoisting cable connected at one end to said boom and intermediate its ends to said dipper to support the dipper, said dipper handle being associated with said cable intermediate said connections so as to shift said handle outwardly 95 by the tension in said cable, and means for shifting said handle inwardly.

6. In a power shovel the combination of a boom, a dipper and dipper handle mounted 100 thereon for swinging and bodily lengthwise shifting movements, a sheave on the inner end of said handle, a hoisting cable associated with the outer end of said handle to 105 swing said handle and with said sheave to maintain an outward thrust on said handle, and a second cable associated with said handle for opposing said thrust to control the lengthwise shifting of said handle.

PAUL BURKE.
